United States Patent Office.

DAVID MUNSON, OF INDIANAPOLIS, INDIANA.

Letters Patent No. 99,461, dated February 1, 1870; antedated January 26, 1870.

IMPROVEMENT IN LIGHTNING-RODS.

The Schedule referred to in these Letters Patent and making part of the same.

To all whom it may concern:

Be it known that I, DAVID MUNSON, of Indianapolis, in the county of Marion, and State of Indiana, have invented a new and useful Improvement in Lightning-Rod Points; and I do hereby declare the following to be a full and correct description of the same, sufficient to enable others skilled in the art to which my invention appertains, to fully understand and construct the same, reference being had to the accompanying drawings, which make part of this specification, and in which—

Figures 1 and 2 are perspective views of my improved lightning-rod point; and

Figures 1^a and 2^a are sections of the same, in lines *x x y y*, figs. 1 and 2.

Like letters of reference indicate like parts in the several figures.

The nature of my invention consists in the peculiar shape of the point, whereby the manufacture is greatly facilitated, their weight considerably lessened, and at the same time the same surface and general features considered necessary in such points retained; also, in the construction of lightning-rod points of sheet-metal, for the purposes hereinafter more fully described.

A, in the drawings, may represent lightning-rods, to which points B are secured.

In figs. 1 and 1^a, I have shown my improved lightning-rod point, as cast in the usual manner. C is the base, which is screwed on to the rod A, and which extends upwardly into the main part *a* of the point. Extending in opposite directions, at an angle to the part *a*, are formed wings *b*, in such a manner that four edges, *c*, are produced, which answer to the four-winged lightning-rod points now in common use.

In figs. 2, 2^a, I have shown a point constructed of sheet-metal, preferably sheet-copper. In this point,

the base C is formed separately from the point proper, and is provided with a slotted shank, *d*, into the slot of which the part *a* of point B passes, and in which it is securely held by rivets *e*. The point proper is formed from sheet-metal, bent into the shape described above, the point being formed by rounding off, which can easily be done by machinery.

This point I plate by insertion into a composition of molten metal, to prevent its liability to oxidize by exposure.

The great advantage of my point is its lightness. On steeples of large buildings, very large-sized points are required, and the great objection to them is their weight.

By the peculiar shape of my point, I am enabled to make them of a great deal less metal, when it is desired to cast them, and if made of sheet-metal, they will be lighter still. In this latter case, their manufacture will be exceedingly easy, and they can consequently be produced at a greatly reduced cost.

In the drawings, I have shown the wings *b b*, as at right angles to the part *a*. It is preferable to construct them in this way, but the angle may be more acute or obtuse, as circumstances and experience may require.

Having thus described my invention,

What I claim as new, and desire to secure by Letters Patent, is—

A lightning-rod point, formed with two wings *b*, extending in opposite directions, and at an angle to part *a*, substantially as and for the purpose described.

DAVID MUNSON.
